United States Patent

Des. 234,845
Patented Apr. 15, 1975

234,845

EXTENSION SPRAY GUN

J. C. Davis, 9818 Hathaway, Dallas, Tex. 75220

Filed Apr. 27, 1973, Ser. No. 354,931

Term of patent 14 years

Int. Cl. D23—01

U.S. Cl. D23—17

Fig. 1

Fig. 2

FIG. 3

FIG. 4

FIG. 1 is a side elevational view of an extension spray gun showing my new design;

FIG. 2 is an elevational view taken from the side opposite that shown in FIG. 1;

FIG. 3 is a rear elevational view thereof; and

FIG. 4 is a front elevational view thereof.

I claim:

The ornamental design for an extension spray gun, substantially as shown.
